CLAIM

I claim the ornamental design for a bucket toy, as shown and described.

DESCRIPTION

FIG. 1 is a front perspective view of the bucket toy, showing my new design;

FIG. 2 is a front elevation view of the bucket toy, wherein the rear elevation view is a mirror image thereof;

FIG. 3 is a right side elevation view of the bucket toy, wherein the left side elevation view is a mirror image thereof;

FIG. 4 is a top view thereof; and,

FIG. 5 is a bottom view thereof.

Broken lines in the drawing views show portions of the bucket toy that form no part of the claimed design.
